United States Patent Office

Des. 227,502
Patented June 26, 1973

227,502

PHONOGRAPH OR SIMILAR ARTICLE

Wilhelm Menke, Schillerstr. 1, Bingen (Rhine), Germany

Filed Dec. 31, 1968, Ser. No. 15,158

Claims priority, application Germany Oct. 10, 1968

Term of patent 7 years

Int. Cl. D14—01

U.S. Cl. D56—4

FIG. 1

FIG. 2

FIG. 3

FIG. 1 is a front elevational view of a phonograph or similar article, showing my new design:

FIG. 2 is a left side top and front perspective view; and

FIG. 3 is a front, top and right side perspective view thereof.

The rear, not shown, is plain and unornamented.

I claim:

The ornamental design for a phonograph or similar article, substantially as shown and described.
